CHAMPAGNE BOTTLE STOPPER

Floyd A. Terwilliger, Rochester, N. Y.

Application September 26, 1957, Serial No. 47,880

Term of patent 14 years

(Cl. D58—10)

FIG. 1.

FIG. 2.

FIG. 4.

FIG. 3.

Fig. 1 is a side elevation of a champagne bottle stopper embodying my new design;

Fig. 2 is a top plan view thereof;

Fig. 3 is an axial section therethrough taken on the line 3—3 of Fig. 1 looking in the direction of the arrows; and

Fig. 4 is an axial section therethrough taken on the line 4—4 of Fig. 2 looking in the direction of the arrows.

I claim:

The ornamental design for a champagne bottle stopper, substantially as shown.
